UNITED STATES PATENT OFFICE.

ADOLPHE C. PETERSON, OF MINNEAPOLIS, MINNESOTA.

DUAL-CYCLE DUAL-FLOW ENGINE.

Application filed November 18, 1922. Serial No. 601,888.

My invention relates to internal combustion engines, and particularly to an engine having a novel form of cycle or combination of cycles and charging means, wherefore it 5 is called a dual cycle dual flow engine.

The principal objects of my invention are to provide an internal combustion engine which will be simple in construction, reliable in operation and maintenance, provide an engine having large efficiency, unusual torque characteristics, unusually free charging at high and low speeds, high economy as applied to automotive constructions, a wide range of flexibility in automotive construction, which will provide an engine easy of control in automotive use in traffic or under unusual conditions and which will in general provide an improved engine for power purposes especially for automotive 20 uses.

The principal devices and combinations of devices constituting my invention are as hereinafter described and defined in the claims.

25. In the accompanying drawings which illustrate my invention, like characters refer to like parts throughout the several views.

Referring to the drawings:

Figure 1, is a view chiefly in vertical cross section on the line X^1-X^1 of Figures 2 and 3, some parts being broken away and some parts being shown in full side elevation to show other parts more readily.

Figure 2 is a view chiefly in vertical cross section at right angles to that of Figure 1, some parts being broken away and some parts being shown in full side elevation, this view being on the line X^2-X^2 of Figure 1.

Figure 3 is a plan view of the engine 40 shown in Figures 1 and 2, some parts being broken away.

Figure 4 is a detail view in vertical cross section through the valve, showing the passage which is shown only in dotted lines in 45 the other figures.

Figure 5 is a detail view of the valve controlling the passage of gas under pressure to the shaft lifting mechanism hereinafter described, this view being in vertical cross 50 section on line X^5-X^5 .

Referring again to the drawings, a main casting 1 has formed integrally with it cylinders 2, two in number and has formed with it two end portions or parts 3 and also 55 a base member 4. The main casting 1 with

its end portions 3 and base 4 constitutes one part which on its two long sides is machined squarely so that radiator side members as hereinafter described may be firmly and closely attached to it closing the chambers and conduits as hereinafter described. The upper end of the main casting 1 is squarely machined and upon this upper end there is secured a head casting 5 which latter supports various parts and has formed in it two independent combustion chambers, each denoted 6, each one connected to one of the cylinders 2 and being divided from the bore of the cylinder by a wall 7. The latter has a port 8 of relatively large size forming a permanent connection between the one chamber 6 and its related cylinder 2. Each cylinder 2 has a reciprocable piston 9 which cooperates with and is adapted to drive a crank shaft 10 by means of connecting rods 11. The crank shaft 10 is revolvably mounted by means of ball or other bearings in the end parts 3. The rear bearing is of such large size that in the assembling of the parts the crank shaft may be inserted from the rear 80 end.

There is for each cylinder 2 a sleeve 13 extending upwardly within the cylinder, the sleeve 13 being formed integrally with the main casting 1. Each sleeve is of such size that a sleeve 12 of the piston 9 reciprocates within the sleeve 13. The piston 9 as shown is a two diameter piston, the sleeve 12 constituting the small diameter piston. Each cylinder 2 has this two diameter piston 90 9-12.

The head casting 5 has for each cylinder 2 two ports, diametrically oppositely located, the two ports of each cylinder permitting communication, as hereinafter described between the space 15 formed in the head casting 5, for each cylinder 2, and two passages 16. The passages 16, two for each cylinder, are formed in the head casting on diametrically opposite side of the combustion 100 chamber 6, and are not connected either of them with the cylinder bore or space 15 or chamber 6 except through the two ports above described which are controlled by valves 14. The valves 14 are located at a slight angle to the vertical as shown, and are poppet valves normally returned to their seats by springs, as shown. The passages 16 each have a form somewhat similar to a U placed on its side. The bend of the 110

U shape is located so that the port controlled by its valve 14 may receive air from that bend or deliver from the cylinder 2 thereto as hereinafter described.

5 In the upper end of each combustion chamber 6 there is located a port controlled by a small poppet valve 17, and providing communication, as so controlled with a conduit 18, common to the two ports, the conduit 18 being formed in the head casting.

Each cylinder has ports 19 in its opposite side walls so located that they are uncovered only when the piston of the cylinder is in its lowermost position, or passing through 15 the position determined by the lower twenty or forty degrees of revolution of the crank upon crank shaft 10. These ports 19 provide for exhaust of the cylinder at such times as uncovered, into two common exhaust conduits 20, one on each side of the cylinders 2.

The space under each piston between the small sleeve 12 and the main cylinder bore may receive air through a port 21, as controlled by a small check valve 22 from a conduit 23, which latter is common to the cylinders 2. Likewise these so-called air compression spaces may deliver through individual ports 24, by check valves 25 to a 20 common conduit 26. These conduits 23 and 26 are cast in the main casting 1.

On the two long sides of the main casting 1 and head casting 5, two so-called radiator side members 27 and 28 respectively, are 30 attached by screws or bolts. These radiator side members are large, so that they substantially cover the entire sides of the main casting, and each has formed in it at substantially the upper half, a box-like chamber 40 which opens to the space immediately adjoining it around the cylinders 2, whereby these spaces form with the spaces about the cylinders 2 water cooling spaces. The members 27-28 have formed in them conduits 45 30, 31, respectively, which are horizontally located in most of their length and may receive air blown by a blower 32 driven by the crank shaft 10.

In each member 27-28 there are cooling 50 tubes 33 placed vertically in the water space, and forming communication between the conduits 30-31 and individual chambers 34 located above the water spaces. The chambers 34 are as many as the passages 16, 55 one related to each passage 16 and forming communication between the passage 16 and some of the tubes 33, whereby air may be received by the passage 34 and passage 16 from the conduits or chambers 30-31.

60 Each member 27-28 has in its upper portion above the chambers 34 individual chambers or passages 35, one related to each passage 16, there being no communication between the passages or chambers 35 and the 65 chambers 34 except through the passage 16.

The passages or chambers 35 of member 27 deliver into an exhaust conduit 36 and the chambers or passages 35 of the member 28 deliver into an exhaust conduit 37. The exhaust conduits 36-37 under one method or 70 cycle of operation deliver directly to the atmosphere, but under the other or two cycle method of operation have no direct delivery to the atmosphere but at their ends are blocked by the hand valves 38 which closes 75 them.

Located horizontally above the head casting 5 and revolvably mounted as hereinafter described is a cam shaft 39 which has two sets of cams, one for two cycle operation and 80 one for four cycle operation. The two cycle cams are adapted to give twice as many operations of the valves related to each cylinder as the cams related to four cycle operation. The cams are adapted to operate 85 rocker arms 40, one for each valve 14. The rocker arms 40 are at their ends remote from the valve stem pivotally mounted and they pass under the cam shaft 39 so that when depressed by the cams they depress the 90 valves. Under all operations or methods of operation, the valves 14 of any one cylinder are simultaneously depressed or opened.

The crank shaft 10 at one end has a mitre gear 41 which through mitre gear 42 drives a vertically mounted rotatable shaft 43, the latter through gears 44, 45 driving the cam shaft 39 in a two to one relation to the rotation of crank shaft 10. The cam shaft 39 is revolvably mounted in 95 two bearings 46-49 which latter are formed, respectively, with small vertically mounted pistons 47 and 50, the latter being slideable vertically in small cylinders 48 and 51, respectively. The cylinders 48, 51 are formed 100 in the head casting 5. The small cylinders 48-51 may receive air or gas under pressure from a receiver 54 as controlled by a hand valve 52. The receiver 54 receives air or gas under pressure from one cylinder 2 by 105 a port controlled by a check valve 55. The valve 52 may be turned by a hand lever 53 by means of a square rod 56 passing through the valve 52 to the near end of the cam shaft 39. The rod 56 has connection with cam 110 shaft 39 by means of a ball bearing and is movable axially as well as rotatable by hand lever 53. The rod 56 bears on it a projection 57 which in the normal position of the valve 52 and rod 56 is turned into sockets 115 or slots in the arm or bracket supporting the housing of the valve 52. The rod 56 is loosely fitted in the square central hole of the valve 52 so that when the cam shaft is lifted slightly the rod 56 may bend somewhat out of its normal relation and likewise the ball bearing connecting rod 56 with cam shaft 39 has a loose fit for this same purpose.

The valve 52 as shown in Figure 5 has two passages cast in it, so that in one posi- 130

tion it permits air to flow from receiver 54 to cylinders 48-51, thereby elevating cam shaft bearings 46-49, and in the other it cuts off this flow and permits the chambers 5 48-51 to exhaust to atmosphere, thereby permitting the cam-shaft bearings 46-49 to lower. This elevating of cam shaft is very slight in degree.

In one end 3 of the main casting 1 there is a transverse horizontal small bore, wherein is located a cylindrical valve 58, which may be turned into either of two positions permitting flow as hereinafter described. The valve 58 has the necessary passages cut 15 transversely through it or in its sides at different portions in its axial length to provide this determination of the flow. The valve 58 may permit flow through the passage or conduit 59 to passage 18. The passages cut in valve 58 at different portions of its length coat with connecting passages formed in the adjacent parts of the end of casting 1 so as to permit of the communications according to the method or cycle of 20 operation and in accordance with the position of the valve 58, as hereinafter described. The portion of the valve 58 shown in Figure 25 4 has a transverse port delivering from the blower casing to the conduit 23. The portion of the valve 58 shown in Figure 1 has several cut out recesses which permit communication according to the position of the valve. The communication permitted by the valve 58 is such as to provide the functioning 30 hereinafter described.

A nozzle 60 in conduit 59 provides for delivery of fuel pumped by fuel pumps 61-40 62 actuated by an eccentric rod from crank shaft 10, an eccentric on the crank shaft causing the reciprocation of pistons within the pumps 61-62. The fuel pumps may receive fuel from any source of supply but flow may be determined by hand valves 63-45 64, thereby providing means for by-passing all or part of the fuel back to the source of supply.

Two electric spark forming or discharge timing devices 65-66 driven in timed relation by shaft 43 by mitre gears, as shown, 50 provide means for distribution of electric current to spark plugs 67, one in each cylinder, the relation being such that when the switch 68 is opened sparks occur only once in two revolutions of the crank shaft, at 55 each spark plug, as for four cycle operation, and when the switch 68 is closed, sparks occur once in each revolution of the crank shaft 10, as for two cycle operation, the sparks being properly timed to occur when 60 compression is complete in the related cylinder 2.

A hand throttle valve 69 in passage 59 provides means for partially throttling or cutting off the passage of carburetted air 65 through passage 59 to passage 18.

In the operation of my device, the crank shaft 10 may be given initial rotation as in any internal combustion, such starting means not being shown in the drawings, however, as it is contemplated that any means may 70 be used. The engine has two methods or cycles of operation, two cycle and four cycle. It is contemplated that the two cycle will be used preferably at the slower speeds when there is heavy pulling for the engine, and 75 that the four cycle may be used at higher speeds and when the pulling or load is lighter.

Describing first the two cycle operation, in this the camshaft 39 is stationed so that 80 the two cycle cams are in position over the rocker arms 40 and so that also the two cycle related cam is over the valve 17 of each cylinder. For this operation the valves 38 (Fig. 3) block the exhaust conduits 36-85 37. For this operation also the electric distributing means is made to deliver one spark each revolution of the crank shaft and the fuel pumps are made to deliver preferably their maximum or near their 90 maximum fuel delivery. The parts in the position to procure this condition, the cycle of operation is as follows: The blower 32 draws continuously from the atmosphere 95 through ports or open spaces of its housing near its central space, air which is by the blower given a few pounds pressure and passed in two major streams through ports 32^a (one only of which is shown) to the passages 30-31 and one minor stream as directed by valve 58 through its port 58^a to the passage 23. The minor stream passes from 100 passage 23 through ports 21 under suction of the upward movement of pistons 9 into the respective air compression spaces under 105 the pistons 9, thence into conduit 26 by way of ports 24 thence as directed by the passages of valve 58 shown in full lines in Figure 1, to conduit 59.

The air current as delivered from conduit 110 26 to conduit 59 is under pressure a few pounds higher than the air pressure from blower 32. The smaller current passing through the conduit 59 receives the delivery of fuel from the fuel pumps which is carried 115 with this current to the passage 18 and thence periodically, is admitted, once during each revolution of the crank shaft 10, to each combustion chamber 6. The admission to the chambers 6 is so timed that it occurs preferably immediately after the piston 9 has closed the ports 19 or just when they are closing or between that closing period and the occurring of the spark in the cylinder. The two major currents of air 120 from the ports 32^a pass into the chambers or passages 30-31 and thence pass upwardly in very small currents through the tubes 33. Some of these small currents pass into each 125 chamber 34 where such small currents unite 130

and pass from the chamber 34 into the passage 16. When the valves 14 are opened, which is approximately just after the exhaust ports 19 of the cylinder are opened, 5 the air current from chamber 34 passes into the space 15 of the cylinder from each of its two passages 16 and thence flows downwardly through the cylinder driving the exhaust gases of combustion before it and 10 thereby filling the cylinder with fresh air. Thus in this two cycle operation the air delivered to chambers 30—31 passes upwardly through the tubes 33 and is admitted to each cylinder space 15 as controlled by valves 14 15 only when the related piston is passing through the lowermost position and when the ports 19 are uncovered. The ports 19 then close and simultaneously or nearly so (but it may be slightly before as construct- 20 ed) the valves 14 close, and the valve 17 is opened to admit some richly carburetted air. Compression then occurs and when compression is complete or nearly so the spark occurs and expansion occurs, the valves all 25 being closed during most of the compression stroke and substantially all of the expansion stroke.

Suppose now that the operator desires to shift to four cycle operation as when the 30 speed becomes faster or the load lighter, he then turns the valve 52 so as to admit some air from receiver 54 to the elevating cylinder 48—51 and the cam shaft is thereby elevated and he then moves the cam shaft 35 axially so as to bring the four cycle cams over the rocker arms 40 and valves 17 and then turns the valve 52 back so as to permit the cam shaft to descend. Having so accomplished the shift, the electric distrib- 40 uting means is made to function as for four cycle operation only. The fuel delivering means is made to deliver a lesser quantity of fuel, and the valves 38 (Figure 3) are moved to open the exhaust conduits 36—37 45 to the atmosphere. In this condition, the cycle of operation is as follows: The blower 32 draws air from atmosphere and delivers the air under only slight pressure directly by ports 32^a into the chambers 30—31 as to 50 the major portion, and as to the smaller portion the air may be passed directly to the conduit 59 or may be compressed by the air compression spaces beneath the pistons 9 as desired. The valve 58 may remain sta- 55 tioned as shown in Figure 1 in four cycle operation also. The air passing through the conduit 59 receives the fuel and passes to conduit 18, thence as controlled by valves 17 to combustion chambers 6, delivery to 60 the latter chambers occurring only once each two revolutions of the crank shaft, that is once for each chamber 6, properly timed with relation to its cylinder cycle. The major portion of the air from blower 32 passing 65 to chambers 30—31, passes upwardly through

tubes 33 to chambers 34 and in four individual streams (two for each cylinder) passes from these four chambers 34 to the passages 16 and thence when the valves 14 of any passages 16 are open to the cylinders 70 and when the valves 14 related to the passages 16 are closed passes through the passages 16 to the exhaust conduits 36—37 and thence to the atmosphere. Thus air is continuously passing to each of the four pas- 75 sages 16, in this four cycle operation, and these four streams of air are continuously passing by the valve 14 related to the passage 16. The air passes through the pas- 80 sage 16 to the atmosphere when the valve 14 is closed and when the valve 14 is open may in whole or in part only pass into the related cylinder space 15 from the passage 16. Under this four cycle operation the valves 14 of each cylinder are held open dur- 85 ing substantially the entire exhaust and suc- 90 tion strokes of the related piston, and during the exhaust stroke the exhaust gases pass from the cylinder through the two ports controlled by the valves 14 to the two pas- 95 sages 16 and are carried by the two air streams therein to the atmosphere. During 100 the suction stroke which immediately fol- 105 lows, the piston sucks the air from the pas- 110 sage 16 on either side of the cylinder, thereby reversing the flow through the two ports controlled by valves 14. As the air passing from tubes 33 to passages 16 is always de- 115 livered under the pressure of the blower, and the flow under this cycle, to atmosphere from conduits 36—37 is very free, exhaust from the cylinders is always carried with the air flow to the atmosphere, and there is immediately available in passages 16 fresh 120 air to enter the cylinders on reversal of the flow under the suction of the piston 9. Each cylinder separately functions, its valves 14 and 17 being controlled so as to open the cylinder to the related passages 16 during 125 exhaust and suction strokes, and to permit delivery from conduit 59 during a short period of the suction stroke, and to close the valves 14 and 17 of the cylinder during substantially all of the compression stroke and expansion stroke. The engine thereby 130 operates as a four cycle engine under this cycle of operation. It is preferable that under either two or four cycle operation the valve 58 be stationed as shown in the drawings so that the minor stream of air to conduit 59 is taken as compressed by the lower side of the pistons into conduit 26. The pas- 135 sages 30—31 under either operation receive air from the blower through ports 32^a.

While I have shown particular devices and combinations of devices in the illustration of my invention, I contemplate that other detailed devices and combinations of devices may be used without departing from the spirit of my invention.

What I claim is:

1. In an internal combustion engine, an engine cylinder, a cooperating piston driving crank shaft, a valve controlled port permitting communication between the cylinder and an adjacent passage, means passing a current of air through the adjacent passage, and means controlling the valve to effect the maintenance of passage through the port during an exhaust stroke and a succeeding induction stroke, and maintaining the valve closed during succeeding compression and expansion strokes.
2. In an internal combustion engine, engine cylinders, cooperating pistons driving a crank shaft, valve controlled ports, one related to each cylinder permitting communication between the cylinder and passages each individually related to one valve and its cylinder, means passing independent or individual currents of air through each passage, and means controlling the valves to effect the maintenance of passage through each port during an exhaust stroke and a succeeding induction stroke of the related cylinder and maintaining the valve closed during succeeding compression and expansion strokes of the related cylinder.
3. In an internal combustion engine, an engine cylinder, a valve governing communication between the cylinder and an adjacent passage, means whereby the adjacent passage may be supplied with air under low pressure, a port in the side wall of the cylinder opened by the piston at the lowermost period of its stroke, and means whereby the valve may be caused to function in a manner causing functioning of the engine upon a two cycle system or may be caused to function in a manner causing functioning of the engine upon a four cycle system, and means whereby under four cycle operation the air stream may have free passage through the adjacent passage to atmosphere carrying any exhausted combustion products with it and may under two cycle operation be blocked to cause entry of the charge to the cylinder for scavenging of the cylinder, and means whereby the cylinder may be periodically charged with fuel.
4. In an internal combustion engine, an engine cylinder and a cooperating piston, a passage adjacent to the engine cylinder, a port between the cylinder and adjacent passage, valve means controlling the passage through the port between the cylinder and adjacent passage, means whereby the engine may be caused to operate so that induction occurs through the valve means during an induction stroke of the piston, compression occurs during a succeeding stroke of the piston, expansion occurs during a succeeding stroke of the piston, exhaust occurs during a succeeding exhaust stroke of the piston, or whereby the engine may be caused to oper-
- ate so that each stroke one way is a compression stroke and each stroke the other way is an expansion stroke and so that at a period in each cycle of compression and expansion an exhausting occurs through ports uncovered by the piston and charging occurs through the port between the adjacent passage and cylinder from the adjacent passage, and means actuated to cause the passage of a current of air to the passage, and means whereby under one system of operation air entering the passage may pass into the port to the cylinder as controlled by the valve means or through the passage to the atmosphere and whereby under the other system of operation the air entering the passage will have egress only through the port to the cylinder as controlled by the valve means.
5. In an internal combustion engine, an engine cylinder and a cooperating piston, a passage adjacent to the engine cylinder, a port between the cylinder and adjacent passage, valve means controlling the passage through the port between the cylinder and adjacent passage, means whereby the engine may be caused to operate so that induction occurs through the valve means during an induction stroke of the piston, compression occurs during a succeeding stroke of the piston, expansion occurs during a succeeding stroke of the piston, exhaust occurs during a succeeding exhaust stroke of the piston, or whereby the engine may be caused to oper-

each cylinder and its related passage during an induction stroke of the related piston, compression occurs during a succeeding stroke of the piston, expansion occurs 5 during a succeeding stroke of the piston, exhaust occurs during a succeeding stroke of the piston, or whereby the engine may be caused to operate so that each stroke of each piston one way is a compression stroke and 10 each stroke the other way is an expansion stroke, and so that at a period in each cycle of compression and expansion of each cylinder an exhausting and charging occurs, and means actuated to cause individual currents 15 of air to pass through each passage, and means whereby fuel is introduced to each cylinder periodically at intervals according to the cycle of operation to produce combustion with each charge compressed in the 20 cylinder.

7. In an internal combustion engine, engine cylinders and cooperating pistons, a passage related to each cylinder, a port between each cylinder and related passage, 25 valve means controlling the passage through the ports between the cylinders and related passages, means whereby the engine may be caused to operate so that induction occurs through the port between each cylinder and 30 its related passage during an induction stroke of the related piston, compression occurs during a succeeding compression stroke of the piston, expansion occurs during a succeeding stroke of the piston, exhaust 35 occurs during a succeeding stroke of the piston, or whereby the engine may be caused to operate so that each stroke of each piston one way is a compression stroke and each stroke the other way is an expansion stroke, 40 and so that at a period in each cycle of compression and expansion an exhausting occurs through ports uncovered by the related piston and charging occurs through the port between the adjacent passage and cylinder 45 from the adjacent passage, and means actuated to cause the passage of air to each passage, and means whereby under one sys-

tem of operation air entering the passages may pass into the ports to the cylinders as controlled by the valve means or through 50 the passages to the atmosphere and whereby under the other system of operation the air entering the passages will have egress only through the ports to the cylinders as controlled by the valve means, and means 55 whereby fuel is introduced to each cylinder periodically at intervals according to the cycle of operation to produce combustion with each charge compressed in the cylinders. 60

8. In an internal combustion engine, a plurality of combustion chambers, a plurality of adjacent passages, a port between each combustion chamber and a related adjacent passage, means actuated to cause the passing 65 of a current of air through each adjacent passage, and means controlling each port to permit communication between the related combustion chamber and adjacent passage during an exhaust period and a charging period and closing the port during a succeeding period, and means for introducing fuel periodically to each combustion chamber. 70

9. In an internal combustion engine, a 75 combustion chamber, an adjacent chamber, means actuated to cause the passing of a current of air through the adjacent chamber, a piston having reciprocation relative to the combustion chamber, and means controlling the port to permit communication between the combustion chamber and the adjacent chamber during an exhaust stroke and a charging stroke of the piston and closing the port during a period comprising a compression stroke and a working stroke of the piston, and means whereby fuel may be introduced into the combustion chamber periodically to produce combustion 80 with each charge of air compressed in the combustion chamber. 85

In witness whereof, I have hereunto set my hand this 25th of October, 1921.

ADOLPHE C. PETERSON.
